United States Patent Office

Des. 232,293
Patented Aug. 6, 1974

232,293

NESTABLE PLATE

Hubert E. Christian and David W. Lee, Phoenix, Ariz.,
assignors to Dart Industries Inc., Los Angeles, Calif.

Filed May 21, 1973, Ser. No. 362,352

Term of patent 14 years

Int. Cl. D7—01

U.S. Cl. D7—1

FIG. 4

FIG. 5

FIG. 1 is a top plan view of a nestable plate embodying my new design;

FIG. 2 is a side elevation view thereof;

FIG. 3 is a vertical cross-sectional view thereof, taken along the line 3—3 in FIG. 1;

FIG. 4 is a bottom plan view thereof; and

FIG. 5 is a front elevation view thereof.

We claim:

The ornamental design for a nestable plate, substantially as shown.
